WORK CLAMPING UNIT

Niels Eldrup, Chicago, Ill.

Application May 5, 1943, Serial No. 485,699

2 Claims. (Cl. 90—59)

1. The principal object of this invention is to provide an improved work clamping unit for use in connection with drill presses, milling machines, and the like.

The devices heretofore employed for this purpose have ordinarily consisted of a flat metal strap which is slotted near its front end to receive a bolt and is fulcrumed at its rear end on a wooden block of the proper height. While such an arrangement provides an effective clamp it usually takes quite a bit of time to set up because unless a block of the proper height happens to be at hand material for one must first be located and then cut to size. Furthermore, a loose block is somewhat difficult to handle because it must be held in correct position with respect to both the strap and the work until after the bolt has been at least partially tightened.

Many special clamping devices have been suggested for the purpose of overcoming these difficulties—as evidenced by numerous prior patents—but very few have been found sufficiently satisfactory to warrant their continued use, either because of the complicated nature of their construction or the fact that when set up they tend in some measure to obstruct the work. As a result of this the practice has been confined almost entirely to the use of makeshift blocks.

The new work clamping unit is extremely simple and inexpensive in construction, is assembled from graduated parts into a temporarily unified arrangement, can be assembled in but a moment's time, will fit any size work and will hold the work securely with minimum obstruction to the same.

While the foregoing statements are indicative in a general way of the nature of the invention, other more specific objects and advantages will be apparent to those skilled in the art upon a full understanding of the new unit.

A preferred embodiment of the invention is presented herein for the purpose of exemplification, but it will of course be appreciated that the invention is capable of being incorporated in other structurally modified forms coming equally within the scope of the appended claims.

In the accompanying drawing:

Fig. 1 is a fragmentary perspective view of the bed of a machine, showing a piece of work clamped to the bed by a pair of the units;

Fig. 2 is a perspective view of one of the units;

Fig. 3 is a vertical section through the unit;

Fig. 4 is a perspective view of the upright block which forms one part of the unit;

Fig. 5 is a bottom plan view of the horizontal

strap which forms the complementary part of the unit; and

Fig. 6 shows several graduated sets of blocks.

The work clamping unit shown in the drawing is a two-piece L-shaped assembly consisting of a horizontal strap 10 and an upright block 11. The strap 10 is made of metal and is provided intermediate its ends with a longitudinally extending slot 12 for the reception of the upper end of a bolt 13. The under side of the front end 14 of the strap serves as a clamping jaw for engagement with the work 15, while the under side of the rear end 16 of the strap is provided with a transversely extending dovetail groove 17 for temporarily interlocked association with the upper end of the upright block 11. The block 11, like the strap 10, is made of metal and is provided at its upper end 18 with a dovetail rib 19 for edgewise insertion in the groove 17. The lower end 20 of the block is provided with a convex bearing edge 21 parallel to the rib 19. A spring projected indexing ball 22 is mounted in the bottom of the groove 17 intermediate the ends of the latter for resiliently yieldable engagement within an indentation 23 in the top of the rib 19.

In securing the work 15 to the bed 24 of the drill press or other machine tool two or more of the clamping units are ordinarily used. Straps 10 and blocks 11 of the required lengths are selected from a graduated assortment of such parts. The ribs 19 on the blocks are slid edgewise into the grooves 17 in the straps, producing temporarily unified L-shaped clamps. After the clamps have been assembled they are placed properly with respect to the work and bolts 13 of the required length are passed through the slots 12 in the straps into holes 25 in the bed and tightened up.

Instead of employing a graduated assortment of integral blocks, as shown in Fig. 6, the blocks can be made up in separable sections by the addition of short extension blocks having dovetail grooves on their lower ends for interlocked association with the ribs 19 on the upper ends of the blocks and dovetail ribs on their upper ends for interlocked association with the dovetail grooves 17 in the straps.

By employing a work clamping unit of the above described construction, both parts of the unit are firmly held together while the work is being clamped in place. Either of the parts can be instantaneously replaced by parts of larger or smaller size, whereby to provide a clamp of any desired character. In the use of the unit the flat design of the top of the same, with the block

11 set in under the rear end of the strap 10, leaves the work practically free from obstruction by the clamp, enabling the operator to get at the work from all directions without difficulty.

I claim:

1. A work clamping unit for use in connection with machine tools of the type having a bolt receiving bed against which a piece of work is adapted to be clamped, comprising a horizontal flat topped strap which is provided intermediate its ends with a longitudinally extending bolt receiving slot and is provided on the under surface of its rear end with a transverse dovetail groove and a resiliently projected indexing member within said groove, and an upright block which is provided at its upper end with a dovetail rib for insertion in said groove and an indentation intermediate the ends of the rib for the reception of said indexing member.

2. A work clamping unit for use in connection with machine tools of the type having a bolt receiving bed against which a piece of work is adapted to be clamped, comprising a horizontal flat topped strap which is provided intermediate its ends with a longitudinally extending bolt re-

ceivng slot and is provided on the under surface of its rear end with a transverse dovetail groove and a resiliently projected indexing member within said groove, and an upright block which is provided at its upper end with a dovetail rib for insertion in said groove and an indentation intermediate the ends of the rib for the reception of said indexing member, 15

ceivng slot and is provided on the under surface of its rear end with a transverse dovetail groove and a resiliently projected indexing member within said groove, and an upright block which is provided at its upper end with a dovetail rib for insertion in said groove and an indentation intermediate the ends of the rib for the reception of said indexing member, said block being provided at its lower end with a convex bearing edge parallel to said rib.
